UNITED STATES PATENT OFFICE.

WILLIAM HENRY BRASHER, OF TORONTO, ONTARIO, CANADA.

GARMENT SUPPORT.

1,414,336.

Specification of Letters Patent. Patented May 2, 1922.

Application filed January 21, 1921. Serial No. 438,936.

To all whom it may concern:

Be it known that I, WILLIAM HENRY BRASHER, a subject of the King of Great Britain, and resident of 37 Howie Ave., in the city of Toronto, county of York, Province of Ontario, in the Dominion of Canada, have invented certain new and useful Improvements in Garment Supports, of which the following is a specification.

- 10 The invention relates to improvements in garment supports as described in the present specification and shown in the accompanying drawings that form a part of the same.
- 15 The invention consists essentially of the novel features of construction whereby a skirt or other garment is provided with a flexible band of stiff material having substantially right angle end projections provided with fasteners for securing said projections in overlapping arrangement.

The objects of the invention are to eliminate the use of hooks and eyes or other like fastening devices, and the consequent annoyance and inconvenience due to said fasteners becoming unfastened or removed, to provide a convenient means for altering the size of the skirt or other band, and generally to provide a garment support which will be inexpensive to produce, simple of manipulation, efficient and durable.

In the drawings Figure 1 is a perspective view of the device in its operative condition, the portions of the skirt being shown in dotted lines.

Figure 2 is a plan view of one end of the device, with a modified form of skirt fastening means incorporated therewith.

Figure 3 is a plan view of the device extended, a portion thereof being broken away.

Figure 4 is a longitudinal sectional view taken on the line A—A of Figure 3.

Figure 5 is a cross sectional view taken on the line B—B of Figure 3.

Figure 6 is a longitudinal sectional view taken on the line C—C of Figure 2.

Figure 7 is a plan view of the central portion of the band showing the means for adjusting the band longitudinally.

Figure 8 is a detail of one end of one of the sections of the device showing the hooking clips.

Figure 9 is a detail of one end of the other section of the device, showing the notches for the clips shown in Figure 8.

Referring to the drawings A represents

a band of very thin metal or like material which may be constructed of a single piece of material but which preferably consists of two sections 1 and 2 adapted to be secured together in overlapping arrangement, the section 1 being provided with lugs 3 adapted to extend around the edges of the section 2 and the section 2 being notched as at 4 to provide a shoulder 5 and being provided with a pair of clasps 6 pivoted at their outer ends to opposite sides respectively of said section to permit of the free ends 7 thereof being movable towards or away from said shoulder 5.

The section 1 is provided with a series of notches 8 along opposite edges thereof at intervals to receive the clasps 6 and hold same in the desired position against further extension of the band.

The band A is preferably turned upwardly slightly towards the outer ends thereof as at 9 so that when secured around the waist of the wearer the top side of said band will be on an even horizontal plane while permitting of the bottom edge spreading slightly to conform to the figure of the wearer.

The band A is adapted to be secured to the inner side of the skirt or the skirt band if desirable and to facilitate sewing said bands together, said band A is preferably provided with a longitudinal series of perforations 10 to receive the threads.

If desirable the band A may be cut away at intervals as at 11 to reduce the weight thereof and to render same more flexible.

12 is a metal strap rigidly secured to the free end of the section 2 and projecting downwardly therefrom at an angle so that the lower end thereof will project outwardly past the end of said section, said strap preferably being secured on the outer side of the band and being provided with perforations 13 to facilitate sewing the skirt thereto.

14 is a hook secured to the section 2 over the strap 12 and being adapted to engage a loop member 15 secured on the free end of the section 1.

16 is a loop or eye member secured on the inner side of the strap 12 intermediate of the length thereof.

17 is a loop or eye member secured on the inner side of the strap 12 adjacent to the free end thereof.

18 is a metal strap secured on the inner side of the free end of the section 1 and

projecting downwardly therefrom at a similar angle to the strap 12, said strap being of less width than the strap 12 and being provided on its outer side with hook members 19 and 20 adapted to engage the loops or eyes 16 and 17 respectively for securing the straps 12 and 18 together, said strap being provided with perforations 21 therealong.

10 The hook 19 is preferably cut away slightly along its outer side as at 22 to permit of slight lateral movement in order to facilitate the fastening or unfastening of the hook 14.

15 In Figure 2 of the drawings a modified means of securing the band A to the skirt is shown in which a strap 23 of flexible material, such as leather, canvas or the like is permanently secured to said band with a portion thereof projecting over the edge of the band and adapted to be sewn to the skirt band.

20 In the use of this invention the band A is sewn to the inner side of the skirt or to the skirt band with the projections or straps 12 and 18 located at the skirt opening, the length of the said band being adjusted to conform to that of the skirt band by raising the clasps 6 free of the shoulder 5 and sliding 25 the sections in the required direction when they may then be secured against further longitudinal extension by simply pressing the clasp inwardly into the adjacent notch 8.

25 When putting on the skirt the strap 12 is placed over the strap 18 and said strap 18 is pushed downwardly until the hooks 19 and 20 enter the loops 16 and 17 respectively and the hook 14 is then secured in the eye 15 thus securely fastening the skirt without the 30 inconvenience of having to locate and fasten a great many hooks and eyes.

35 What I claim is:—

1. A garment support comprising a pair of sections of yieldable material secured together in longitudinally overlapping position and adjustable longitudinally in relation to each other, and straps secured to the free ends respectively of said sections and projecting therefrom at right angles, one of 40 said straps being provided with projections constituting hooks and the other of said straps being provided with loops to receive said projections for securing said straps together in superposed position.

45 2. A garment support comprising a pair

of flexible sections adapted to be secured together in longitudinal overlapping arrangement, one of said sections being notched at intervals along opposite side edges adjacent to the inner end thereof and having lugs 60 adapted to extend around the other of said sections, said other section being provided with a single pair of oppositely disposed notches, and clasps pivoted to opposite sides of the last mentioned section adjacent to the 65 extreme inner end thereof and adapted in the overlapping arrangement of said sections to be brought into register with one or other of the notches in the first mentioned section for locking said sections against further 70 longitudinal extension, and means for detachably securing together the free ends of said sections.

3. A garment support comprising a pair 75 of flexible sections adapted to be secured together in longitudinal overlapping arrangement, one of said sections being notched at intervals along opposite side edges adjacent to the inner end thereof and having lugs adapted to extend over the edges of the other 80 of said sections, said other section being provided with a single pair of notches located in opposite side edges adjacent to the end thereof, clasps pivoted to opposite sides of the last mentioned section at the outer 85 ends of the notches therein and having their free ends movable into or out of said notches and adapted in the overlapping arrangement of said sections to be brought into register with one or other of the opposing sets 90 of notches in the first mentioned section, straps secured to the free ends respectively of said sections and projecting therefrom at substantially right angles, hooks secured to one of said straps at intervals therealong 95 and adapted to engage eye members carried by the other of said straps for securing said straps in superposed relation to each other, the innermost of said hooks being cut away along its outer side, and fasteners secured on 100 opposite sides of the free ends of said sections respectively for securing together said ends in superposed position.

Signed at the city of Toronto, this 30th day of November, 1920.

WILLIAM HENRY BRASHER.
